UNITED STATES PATENT OFFICE.

MAURICE LACHMAN, OF NEW YORK, N. Y., ASSIGNOR, BY MESNE ASSIGNMENTS, TO BETHLEHEM STEEL COMPANY, OF BETHLEHEM, PENNSYLVANIA, A CORPORATION OF PENNSYLVANIA.

METAL WHEEL.

1,391,064.

Specification of Letters Patent. Patented Sept. 20, 1921.

Application filed November 17, 1919. Serial No. 338,420.

To all whom it may concern:

Be it known that I, MAURICE LACHMAN, a citizen of the United States, and a resident of New York, in the county of New York and State of New York, have invented 5 certain new and useful Improvements in Metal Wheels, of which the following is a specification.

My invention relates to the construction 10 and method of manufacturing metal wheels with the spoke and hub or rim parts integral.

The object of my invention is to utilize 15 rolled metal bars in the manufacture of wheels and more particularly forms of bar which may be rolled with flanges at or near the edges thereof respectively.

As an example of the form of bar utilized 20 in carrying out my invention I have shown a channel bar.

The invention consists essentially in constructing the wheel from a section or length 25 or bar the two edges of which are bent to cause the flanges to serve as the rim part of the wheel while the web or base of the bar between the edges is subdivided to form two sets of spokes integrally united in the hub structure.

The invention consists essentially in constructing 30 the wheel from a length of bar having flanges projecting from one face thereof, the base or body being utilized as to one portion in the structure of the hub or rim and as to another part or portion 35 of said base or body is divided to form spokes, while the flanges or ribs are employed in either portion of the wheel, to wit: either the rim or hub. If the floor or base be provided with flanges, projecting therefrom 40 at its edges and from its intermediate portion as well, the latter, as will be hereinafter described, may be utilized in the rim or hub structure. The channel bar illustrated is shown as provided with 45 such intermediate flanges or ribs but, as will be obvious to those skilled in the art from the subjoined description, the invention is capable of being carried out by using a bar having flanges or ribs at or near its edges 50 only.

In the accompanying drawings:

Figure 1 is a cross-section of a form of

channel bar suitable for use in carrying out my invention.

Fig. 2 is an inverted plan view of a portion 55 of the length or section of bar employed in making the wheel and shows the manner of subdividing the bar to form the spokes and the ends of a hub box when the invention is utilized in making a wheel 60 wherein the barrel and ends of the hub box are integral.

Fig. 3 is a cross-section on the line 3—3 Fig. 2.

Fig. 4 shows the manner of bending up the 65 body or base of the bar to bring the subdivisions into the relation of spokes.

Fig. 5 shows the completed wheel and

Fig. 6 is a cross-section of a portion of 70 the wheel on the line 6—6 Fig. 5.

Fig. 7 is a cross-section of a modified form of channel bar that may be used in carrying out my invention.

Fig. 8 is a plan of a portion of the same 75 bar showing the manner of subdividing it preparatory to bending the body of the bar to the circumference of the rim.

Fig. 9 is a side elevation of a wheel made 80 from the subdivided blank shown in Fig. 8.

Fig. 10 is a cross-section on the line 10—10 Fig. 9.

Referring to Fig. 1, the channel bar is shown with four ribs or flanges two of which indicated at 1 are at or near the edges thereof while two others, 1', extend from 85 an intermediate portion of the base or body of the bar and are located respectively at opposite sides of a portion 2 of said base or body which is utilized as the barrel of the hub. The remaining portions 2' are utilized 90 in the formation of the spoke portion of the wheel.

The channel bar is preferably a rolled 95 channel bar, a suitable section or length of which, to form preferably the whole wheel, is taken and subdivided on the lines 3 as indicated in Fig. 2, which lines of division extend from portion 2 of the bar outwardly in opposite directions, to the edges thereof, including the flanges or ribs 1. When a 100 channel bar having the intermediate flanges or ribs 1' is employed, and portion 2 is utilized in the hub, said lines of division preferably include also the flanges 1' and

when required by the height of flanges 1', said flanges are also cut away in the sections or parts 4 (see Fig. 3), to accommodate the blank to the operation of bending the section 2 to the circumference of the hub barrel.

The section or length of channel bar having been subdivided as shown, portions 2' are bent up as indicated in Fig. 4 to cause them to assume the relation of spokes to the part 2 in the finished structure and to bring the flanges 1 into the relation of rim to said spokes, said flanges or spoke terminals ordinarily forming, however, a means for support and attachment of a separate rim 5 such as indicated in Figs. 5 and 6, said rim being attached by welding or otherwise to the spoke ends 1. The portion 2 of the bar is bent in any suitable way to the circumference of the hub barrel, thereby causing sections 1' to meet and form the ends of the box hub while the divisions 2' integral with said hub are caused to radiate therefrom as spokes, to whose rim ends formed by flanges or ribs 1 the supplemental rim proper 5 is secured.

Obviously the flanges 1' may be omitted, the flanges 1 being retained and the part 2 be utilized or merged in the hub structure in any desired way, as well understood in the art.

Obviously likewise the flanges 1 may be omitted and the flanges 1' retained, the spokes 2' being connected in the rim in any desired way.

35 In the channel bar, Fig. 7, the intermediate flanges 1' instead of projecting from the same side of the bar as flanges 1, project from the opposite side and the bar extends slightly beyond the location of the flanges 1. 40 In this modification of my invention the portion 2 of the channel bar is utilized to form the continuous rim instead of the continuous hub, but the sections of 2' are utilized as before in forming the spoke portion of the wheel and the flanges 1, instead of being used as a portion of the rim are used as a portion of the hub. In this instance the portions of the body between the flanges 1 and the extreme edge of the channel bar may 50 be utilized to form the ends of the hub box.

To prepare the channel bar for use it is subdivided as to portion 2' and flange 1 as indicated in the plan view Fig. 8, the lines of subdivision starting from or at the flanges 1' or from the two sides of the portion 2 utilized in the rim. In addition parts are removed as indicated at the spaces 7 to allow portion 1' to come together as a spoke member or disk of the wheel when the part 2 is 60 bent to the circumference of the rim, the parts 2' at the time of bending being arranged to project from the part 2 transversely. Preparatory to the bending operation the bar having been subdivided as indicated in Fig. 8, the parts 2' to either side of

the part 2 are bent down, thus causing them to assume practically the relation shown in Fig. 10, wherein, as will be seen, the flanges 1' are brought into practically the same plane with the part 2 and may be bent with the section or part 2 to the circumference of the rim in the same operation, whereby the rim is composed of the part 2 and said flanges. The bending down of the sections or parts 2' also brings the flanges 1 into the relation indicated in Fig. 10 and brings the portions of the bar exterior to the flanges 1 into position shown, so that they may constitute, in conjunction with the flanges 1, the ends and circumference of the box hub as plainly shown in Figs. 9 and 10. The assembling of them and the disposition of the parts 2' in the relation of spokes to the completed structure is brought about in the operation of bending the part 2 to the circumference of the rim. The edges of the flanges 1 where they meet in the hub may be welded together if desired. Also, as will be obvious, the portions of the base of the channel bar beyond the flanges 1 might be omitted. Also, as will be obvious, the flanges 1' might be omitted although it is desirable to use the same in order to give an overhang to the rim.

The specific form of wheel and method of construction illustrated in Figs. 7 to 10 inclusive is not herein specifically claimed but will form the subject of specific claims in an application for patent to be filed as a division of the present application.

What I claim as my invention is:—

1. A metal wheel consisting of a channel bar formed with four flanges, the two inner flanges of which together with the intermediate portion of base are bent to form the hub while the spoke part consists of the remaining portion of the base and flanges divided and bent up to form separate spokes terminating at the rim in divided portions of flanges.

2. A metal wheel having a continuous hub portion and spokes integral with one another, said hub portion comprising a portion of the base and two flanges of a channel bar and said spokes being formed of the remaining portion of the base of said channel bar divided and bent to extend radially from the portion of base embodied in the hub.

3. A metal wheel having a continuous hub portion and spokes integral with one another, said hub portion comprising a continuous undivided part of a rolled channel bar bent to the circle of the hub and said spokes comprising the remaining part of the bar and the flanges divided and bent to extend radially from the part embodied in the hub.

4. A metal wheel consisting of a section of rolled channel bar having two exterior flanges and two intermediate flanges, a por-

tion of base between the latter flanges being bent to the circumference of the hub to form in conjunction therewith the hub structure while the portions of base exterior to the hub portion are subdivided and bent to form spokes radiating from and integral with the hub and having spoke heads consisting of the external flanges of the channel bar.

5. A metal wheel comprising a section of 10 channel bar rolled with two flanges intermediate its edges, the hub of the wheel embodying the portion of base between flanges bent to the circumference of the hub and subdivisions of said flanges assembled by the bending into the sides of the hub box while the 15 portions of the base external to said flanges are subdivided and form spokes integral with the hub.

6. A metal wheel embodying in its structure 20 a length of channel bar, flanges of which together with the intermediate portion of the bar, form the hub box while the remaining portion of the bar subdivided and bent up, forms the spokes.

25 7. A metal wheel embodying in its structure a length of channel bar having a flange at one edge and another flange between the same and the opposite edge, the latter flange and a portion of the bar beyond the same being embodied in the hub part of the wheel while the remaining portion of bar and the edge flange are subdivided and bent up to 30 form spokes the ends of which consist of subdivisions of the flange and form bearings 35 for a metal rim.

8. A metal wheel consisting of a section of 40 rolled metal bar provided with flanges, the intermediate portion of the web or base of said bar being continuous and bent longitudinally to the circumference of a circular portion or element of the wheel structure while the portions of the web exterior to 45 said continuous part are subdivided and form spokes, the flanges of said bar being embodied in a portion or element of the wheel in which said spokes terminate.

9. A metal wheel consisting of a section of 50 rolled metal bar provided with flanges at its edges, a portion of the web or base of said bar being subdivided to form two sets of 55 spokes integrally connected in an intermediate undivided portion of the base circumferentially continuous and bent to form one portion of the wheel structure, the flanges at the edges of the bar being embodied in the other portion of the wheel structure as and for the purpose described.

10. The method of constructing a metal 60 wheel from a length of channel bar having flanges intermediate its edges consisting in subdividing the portions of bar external to the flanges, bending up the subdivisions to extend transversely to the plane of the portion of bar between flanges and bending the

portion of bar between flanges to form a 65 box hub and cause the subdivisions to radiate therefrom as spokes.

11. The method of constructing metal 70 wheels from sections or lengths of channel bar provided with two flanges intermediate its edges, consisting in subdividing said flanges and the portions of bar external to the same, bending up the divided portions so that they will extend transversely to the 75 plane of the portion of base between the divided flanges, and bending the latter portion of the base into the form of the hub to bring the divided portion of the flanges into proper assembly as sides of the box hub and to cause the divisions of the remaining portion 80 of the base to diverge radially into spokes terminating in the rim.

12. The herein described method of constructing metal wheels from sections or 85 lengths of channel bar having four flanges extending therefrom in the same direction, consisting in subdividing two of said flanges to form in connection with the intermediate portion of the base the hub portion of the wheel, subdividing the remaining portion of 90 the web and the external flanges to form the spokes, and bending the undivided portion of the web into the circumference of the hub and bending up the divisions of the base to place then in the relation of spokes to the 95 hub.

13. A metal wheel formed from a section 100 of metal bar having flanges projecting from an intermediate portion thereof, said intermediate portion being bent into the circumference of one element of the wheel while the portions of the web or base exterior to said flanges are subdivided to form two sets of spokes connecting the undivided portion with the other element of the wheel. 105

14. A metal wheel consisting of a section 110 or length of channel bar rolled with four flanges, two of the flanges and subdivisions of the web being embodied in the spoke and rim construction while the remaining two flanges are embodied in the hub structure.

15. A metal wheel consisting of a section 115 of rolled metal bar provided with flanges at its edges, the web or base of which is subdivided to form two sets of spokes integrally connected in one portion of the wheel structure while the flanges are embodied in the other portion of the wheel structure as and for the purpose described.

16. A metal wheel consisting of a section 120 of rolled channel bar having flanges at its edges and having a portion of its base subdivided inwardly toward the center from the edges to constitute two sets of spokes, the flanges of said bar being embodied in 125 one part of the wheel structure and the intermediate undivided section of the base in another part of the wheel structure, said

parts being connected by the divided portions of the base radiating from one to the other of said parts.

17. A metal wheel formed of a section or 5 rolled metal bar having flanges at both edges, said flanges constituting together a rim part of the wheel while the spokes in two sets consist of the subdivided portions of the web or base and are joined in an undi-

vided portion thereof constituting a portion 10 of the hub structure.

Signed at New York, in the county of New York and State of New York, this 12th day of November, A. D. 1919.

MAURICE LACHMAN.
